UNITED STATES PATENT OFFICE.

ALFRED SAMUEL, OF NEW YORK, N. Y.

SELF-ADHESIVE CIGAR-PATCH AND METHOD OF MAKING SAME.

SPECIFICATION forming part of Letters Patent No. 631,615, dated June 13, 1900.

Application filed February 13, 1897. Serial No. 623,715. (No model.)

To all whom it may concern:

Be it known that I, ALFRED SAMUEL, a citizen of the United States, and a resident of New York city, in the county of New York and State of New York, have invented a certain new and useful Self-Adhesive Cigar-Patch and Method of Making Same, of which the following is a specification.

As is well known, cigars carried about in pockets frequently become partially broken or their wrappers are so fractured or damaged as that the cigars are unfit for use, the broken or fractured portions admitting the air, and thereby rendering difficult or impossible the drawing through into the mouth of the smoke. When the "drawing" qualities of the cigar have thus been impaired, most smokers are accustomed to cast the cigar away, while others have heretofore, in some instances, attempted to repair the break by the use of an ordinary piece of tissue or newspaper, which is wetted and wrapped about or laid over the broken portion of the cigar. This mode of remedying the difficulty is extremely unsatisfactory, because in the first place the tissue or other paper soon becomes dry and detaches itself from the cigar, and in the next place even if it should remain in position it emits a very disagreeable odor and produces an equally-objectionable taste when the fire of the cigar has reached the paper and caused it to burn with the tobacco of the cigar.

My invention has for its ultimate object the production of an article of manufacture which is so prepared that it may be quickly and conveniently used by the consumer to mend or repair broken cigars and which at the same time shall be entirely free from any objectionable taste or odor.

Tobacco itself is the only substance or ingredient known to me which may be employed for repairing purposes without being open to the objection of disagreeable odor or taste; but tobacco is of such a nature that without previous special manipulation or preparation it does not admit of being used for the purpose set forth. Hence another object of my invention relates to a mode of treatment of the tobacco by which the finished article or product is rendered peculiarly fit and adapted for the purpose intended.

The finished product or new article of manufacture consists of a tobacco-leaf or pieces of a leaf or leaves rendered tough and self-adhesive, as will be more fully explained hereinafter. According to ordinary processes of working tobacco-leaves it is impossible to provide these qualities and which are essential to render the article capable of the use for which it is desired. The tobacco-fabric must of course be so made that it may be kept in stock and also carried about the person of the smoker, and hence must necessarily always be in a dry condition. Again, to enable the fabric to be used to repair breaks it must be capable of handling without readily breaking, cracking, or crumpling, and it must also be capable, after having been wet with the tongue or otherwise, of being bent or partially wrapped around the cigar to cover the break or air-hole and to receive the necessary pressure of the fingers to cause it to adhere to the wrapper without fracturing or bursting.

It is of course well known that in the manufacture of cigars tobacco-leaves can be handled and worked only while in a moist or dampened condition, because when the tobacco is in a dry condition it is rendered so brittle that a mere touch will turn it into fragments or even dust and for the further reason that when tobacco is in a dry state it is in a shriveled or wrinkled condition, which, even if it could be handled or worked, would preclude its use for wrapping purposes. It has therefore been one of the main objects of my invention to so treat the tobacco as that when dry it shall remain in a substantially flat, even, and smooth condition, and at the same time to also toughen or strengthen it, so that it may be handled almost if not quite as freely as when in a moist condition. Until I had attained this object it had not been possible for me to produce the new article which I have denominated a "self-adhesive tobacco patch for cigars."

In carrying out my invention I employ two cylinders or rollers covered with vulcanized rubber or other suitable soft material. These cylinders or rollers are held pressed together as closely as possible in order to exclude from the wet tobacco-leaf all superfluous moisture. The leaves, previously wet by dipping them into a tub of water, are run or

passed between the said cylinders or rollers and are thereby flattened out and rendered comparatively smooth or even, while at the same time all excessive moisture is wrung or 5 pressed out of them. Before the leaf is permitted to dry and thereby become wrinkled again I apply to one side of the leaf by means of a brush or cloth an adhesive substance, preferably a solution of gum-tragacanth and 10 water, after which application the leaf is cut between the veins into square or other shaped pieces, which are allowed to dry, when they are then packed in small tin or other boxes ready for the market. The application of the 15 gum or adhesive coating acts to strengthen, toughen, or render tenacious the tobacco-leaf, thus permitting it to be handled readily when dry, while at the same time the fabric is maintained in the comparatively smooth and 20 even condition desired for future use. In addition to this, the gum when dry is capable of being readily moistened and dissolved by the tongue or by a little water, and thus the fabric is rendered self-adhesive when applied 25 to the cigar.

While I have found in practice that the solution described may be employed both to increase the cohesive strength of the fabric and also as a suitable and most desirable adhesive 30 agent to enable the instantaneous application of a patch to the broken cigar, I desire it to be understood that in so far as the main feature of my invention is concerned the stiffening or strengthening quality imparted to 35 the fabric may be effected by a different ingredient from that which is employed to render the fabric self-adhesive. In other words, the tobacco may undergo two distinct operations, one to strengthen or toughen it and the 40 other to render it self-adhesive, and in carrying on the first-named operation a substance or ingredient may be employed which would not also render the fabric self-adhesive, and I would also have it understood that while I 45 use in practice and have found the solution described the most satisfactory one for the purpose of rendering the tobacco self-adhesive I do not wish to be limited to the employment thereof to the exclusion of other suitable 50 solutions or adhesive agents.

By reason of the strengthening or toughening process the finished product may be readily handled, no matter how old it is or dry it may become. The consumer or user 55 may with a knife or pair of scissors cut from the square or piece a section or patch of the proper size to cover the break or tear in the cigar-wrapper, and then by wetting the same he may cause the patch to adhere to the cigar 60 over the opening, and thus in a moment's time repair the damage and place the cigar in perfect condition for smoking. Since these patches are made of tobacco and of a good

quality, the cigar may be smoked up to and past the patch without any impairment of the 65 taste of the cigar or the discovery of any disagreeable odor due to the presence of the patch.

It will thus be seen that by my invention an ever-ready means is provided for the cigar-smoker by which his damaged or broken cigars may be quickly and thoroughly repaired by himself, thus avoiding the loss of cigars which might otherwise ensue. These patches are comparatively of trifling cost and by their 75 use smokers may be saved considerable loss on account of imperfectly-made cigars or cigars which may have become broken by dropping them or by carrying them around in the pocket.

What I claim as new, and desire to secure by Letters Patent, is—

1. As a new article of manufacture, dry, self-adhesive tobacco patches for repairing cigars; substantially as set forth. 80

2. As a new article of manufacture, a dry, self-adhesive patch made of leaf-tobacco and having on one side a strengthening or toughening coating; substantially as set forth. 85

3. As a new article of manufacture, a dry, smooth, tobacco leaf or piece having a strengthening or toughening coating applied thereto; substantially as set forth. 90

4. As a new article of manufacture, dry and smooth tobacco leaves or pieces having applied on one side thereof a strengthening and adhesive coating or substance; substantially as set forth. 95

5. The herein-described process of strengthening or toughening tobacco-leaves, which 100 consists first in wetting the leaves, next in pressing the superfluous moisture therefrom and in smoothing out the leaves, and in then applying a strengthening or stiffening ingredient to the leaves to prevent them from 105 shriveling or rewinkling and to enable them to be readily handled when dry; substantially as set forth.

6. The herein-described process of treating tobacco-leaves which consists first in wetting 110 the leaves, next in pressing the superfluous moisture therefrom and in smoothing out the leaves, and in then applying a gum to the leaves on one side, whereby the leaves when permitted to dry are strengthened or toughened and maintained in their flat, smooth 115 condition and are at the same time rendered self-adhesive; substantially as set forth.

Signed at New York city, in the county of New York and State of New York, this 15th 120 day of February, A. D. 1897.

ALFRED SAMUEL.
